Primary Examiner — Elizabeth J Oswecki*(74) Attorney, Agent, or Firm* — Murphy, Bilak & Homiller, PLLC(57) **CLAIM**

The ornamental design for a power semiconductor module, as shown and described.

DESCRIPTION

FIG. 1 is a top, side perspective view of a power semiconductor module, showing our new design;

FIG. 2 is a front elevation view thereof;

FIG. 3 is a top plan view thereof;

FIG. 4 is rear elevation view thereof; and,

FIG. 5 is a side elevation view thereof.

All surfaces not shown form no part of the claimed design.
